CONVERTIBLE CRAWLER SHOVELS AND LIKE MACHINES

Cecil Craven Langstroth, Montreal, Quebec, Canada, assignor to Dominion Engineering Works Limited, Montreal, Quebec, Canada

Filed Mar. 14, 1957, Ser. No. 646,009

7 Claims. (Cl. 105—215)

This invention relates to power shovels and like machines and particularly to means for converting such machines from crawler tread operation to spool wheel operation and the converse.

Power shovels generally follow a well established design insofar as their main operating characteristics are concerned and are provided with travelling gear to suit the work for which they are primarily built. However, it often occurs that an operator has work to be done by the power shovel which requires that the shovel be equipped with crawler treads for working on the ground and for other work requiring the shovel to be equipped with wheels for operating on rails. This is particularly the case with railway operators where one class of work is ditching along side the railroad tracks where the power shovel can be operated from the tracks and where other work beyond the normal reach of a power shovel confined to tracks necessitates the use of a power shovel equipped with crawler treads. In such circumstances the cost of providing separate shovels with different type treads is considered too high and further, in most cases, it involves the use of two flat cars to transport the shovels to the work location.

Power shovels have been made convertible in the past by providing a main travelling gear of either the crawler or wheel type and having an auxiliary travelling gear of the alternate type to the main gear, this auxiliary travelling gear usually being controlled by displacement mechanism, displacing one travelling gear vertically with relation to the other, or the displacement mechanism may operate some form of out-rigger gear to swing the auxiliary travelling gear up and out from the machine. Such combinations of main and auxiliary travelling gear are generally considered impractical particularly for railroad work where the machine has to be transferred on and off a railroad flatcar.

The present invention consists essentially in providing, in a power shovel, a main truck frame capable of taking either crawler tread or wheel travelling gear, the alternative forms of travelling gear being arranged to fit into the same forked ends of the side members of the main frame and to be aligned on the same centres. The conversion of the machine from wheel to crawler tread travelling and conversely being carried out on a railroad flatcar provided with a set of rails and crawler tread supporting timbers laid parallel with and on both sides of the rails and whose top surface is flush with the top of the rail to enable the crawler tread to be maneuvered into place and be fitted to the machine without interference from the rails. Both the wheel assembly and the crawler track assembly being equipped with similar driving and non-driving shaft assemblies which fit into the same forked ends of the machine side frames and are tensioned similarly. The alternative gear not in use is stored on the top of the flatcar between the rails and can be maneuvered thereon by connecting the parts by slings or cables to the forks of the shovel dipper.

The object of the invention is therefore to provide a

2

power shovel on which the travelling gear can be quickly and efficiently exchanged from crawler tread to spool wheel type without the use of built in extension or retraction outrigger gear.

5 A further object of the invention is to provide a convertible power shovel particularly suited to operate on or off a railroad flatcar with either crawler tread or spool wheel type travelling gear.

10 A further object of the invention is to provide crawler tread or spool wheel type travelling gear which can be readily connected with driving gear common to both types of travelling gear.

15 A further object of the invention is to provide a power shovel whose main frame is made suitable to take crawler tread or wheel shaft assemblies and to hold these shaft assemblies to a uniform distance between centres.

20 A further object of the invention is to provide a railroad flat car having rail and tread surfaces of uniform height providing working surfaces upon which the wheels or crawler treads of a power shovel can be set for quick replacement with each other.

These and other objects of the invention will be apparent from the following specification and the drawings attached thereto in which:

25 Fig. 1 is a side elevation showing in outline a power shovel mounted on a railroad flatcar and showing a crawler tread in place under the side frame of the power shovel and attached to the shovel member for maneuvering into place preparatory to fitting the tread over the idler wheels of the truck frame.

30 Fig. 2 is a partial plan view of one side of a power shovel main frame fitted with spool wheels and supported on rails on a railroad flat car and showing the driving gear shaft assembly in section.

35 Fig. 3 is a side view of the power shovel main frame side member shown in Fig. 2 and showing the crawler tread idler wheels mounted thereon.

40 Fig. 4 is a driving end view of the assembly shown in Figs. 2 and 3.

45 Fig. 5 is a partial plan view similar to Fig. 2 but showing the main frame of the power shovel equipped with a crawler tread.

50 Fig. 6 is a side view of the power shovel main frame side member fitted with the crawler tread shown in Fig. 5.

55 Fig. 7 is a driving end view of the assembly shown in Figs. 5 and 6, with the frame raised to allow the treads to be drawn into position.

60 Fig. 8 is a horizontal section of the non-driving end of the truck assembly taken on the line 8—8 of Fig. 6.

65 Fig. 9 is a diagram showing a drive applied to the wheels at both ends of the shovel.

Referring to the drawings, the power shovel 5 is shown in outline only in Fig. 1 and is mounted on a railroad flatcar 6. The top surface 7 of the flatcar 6 is provided with a pair of rails 8 set at a specified gauge from each other and symmetrically about the centre line of the flatcar. Each rail is flanked on either side with the heavy timbers 9, the top surface of which is flush with the top surface of the rails 8, and are spaced outwardly of the rail 8 to provide clearance for the rims 10 of the spool wheels 11.

70 The power shovel 5 hereinafter described in detail is primarily for use in railroad work and has therefore to be easily convertible from rail to crawler tread and the converse. The frame of the power shovel 5 consists of two side members 12 and suitable cross members 13. The side members are composed of a pair of reinforced channel members 14 set back to back and spaced apart to provide clearance for the spool wheels 11 and 11a or the crawler tread engaging drive sprocket 15 and the idler sprocket 15a.

75 The ends of each side member 12 are forked horizon-

tally at 16 to provide seats for the adjusting shaft bearing blocks 17, the inner ends of the slots 16 being blocked off by the transverse webs 18 extending vertically between the web and the top and bottom flanges 14a and 14b of the side members 12. The shaft bearing blocks 17 are retained within the slots 16 by the end keeper plates 19 and are held in horizontal adjustment by the adjusting screws 20 passing through the transverse webs 18. The adjusting screws 20, adjusting the position of the rotating driving axles 21 are anchored in the boss 22 and are locked in the adjusted position by the nuts 23 and 23a on either side of the transverse web 18 while the adjusting screws 20a holding the non-driving end shaft bearing blocks 17a are held by the single nut 24 which is anchored against rotation after the bearing adjustment has been set. Where the non-driving axle 25 carries a freely journaled idler crawler tread sprocket 15 as generally shown in Fig. 8, the sprocket 15a is journaled on the sleeve bearing 26 and it is preferable that the shaft 25 be non-rotative. In this case the adjusting screws 20a are passed through the bearing blocks 17a and the shaft 25.

The drive shaft 27 drivably connected with the main drive of the power shovel 5, drives the sprocket 28 and through the drive chain 29 rotates the sprocket 30 and the driving axle 21.

In order to obtain the maximum traction effect from the spool wheels 11 and 11a, the axles 21 may be joined together by the floating axle 21a while the axles 25 may be joined together by the floating axle 25a as shown in the diagram Fig. 9. In this case, instead of the drive chains 29 being connected to each of the axles 21, one drive chain is connected to one of the axles 21 while the other drive chain is connected to one of the axles 25, thereby applying traction to each of the wheels 11 and 11a.

A pair of idler wheels 31 are journaled in the bearings 32 on the top flanges 14a of each truck frame side member 12 and carry the crawler tread 39, formed by the links 33, between the sprockets 15 and 15a above and clear of the truck side members 12. Similar idler wheels 34 are journaled in the bearings 35 on the underside of the bottom flanges 14b of the truck side members 12 to support the truck frame when the crawler treads are in use. The idler wheels 31 and 34 are individually located between the pairs of spaced channel members 14 constituting the side members 12 of the truck frame and the lower idler wheels 34 are located vertically such that the lowest point of their rims are slightly above the top level of the rail 8 when the truck is fitted with the spool wheels 11 and 11a, as seen in Fig. 3.

It will be noted that the tread centre line A—A shown in Figs. 2 and 5, whether for spool wheel drive or crawler tread drive of the power shovel, remains in the same position, i.e., centered with the rails 8 and that the drive to the driving shaft also remains in the same location. The drive shaft assembly for the spool wheel drive consists of the axle 21 to which is keyed a chain sprocket 30 and a spool wheel 11 and a pair of shaft bearing blocks 17 complete with adjusting screws 20, while the substitute drive shaft assembly for the crawler tread drive consists of the shaft 21 to which is keyed a chain sprocket 30 and a tread sprocket 15 and a pair of shaft bearing blocks 17 complete with adjusting screws 20. Similarly the non-driving axle assembly for the spool wheel drive consists of the shaft 25, a journaled spool wheel 11a and a pair of shaft bearing blocks 17a complete with adjusting screws 20a.

The fabricated structural steel frame described, with its spaced apart channel side members giving clearance for the wheels 11 and 11a and the tread sprockets 15 and 15a, may be replaced by a cast frame having suitable recesses to give clearance for the wheels and tread sprockets and

also have suitable pockets for the adjustable shaft bearing blocks 17 and 17a.

Having described in detail the constructional features of the power shovel drive for either spool wheel drive or crawler tread drive, the method of converting the power shovel from one form of drive to the other, will now be described.

Presuming that the power shovel is fitted with spool wheels 11 and 11a and running on the rails 8 on top of the flatcar 6 with the crawler tread strands and substitute shaft assemblies stored on the top of the flatcar. The order of conversion will be as follows:

Conversion of one side of the truck is completed before work is started on the other side of the truck.

(1) Move the power shovel to the extreme end of the flatcar 6 which will place the roller drive chain end of the truck frame 12 facing the stored crawler tread strands. The wheels 11 and 11a being blocked in this position by the wheel chocks 42.

(2) Connect a sling 36 to the crawler tread link pin 37 which is nearest to the power shovel and hook the other end of the sling 36 onto one tooth of the shovel dipper 38.

(3) Lift the crawler tread strand 39 as high as possible with the dipper 38 and swing the strand over and onto the top of the timbers 9 as much as possible. Lower the end of the strand 39 and remove the sling 36. Complete the lineup of the treads with the dipper 38 or by means of crowbars.

(4) Move the power shovel to within 18 inches of the crawler tread strands.

(5) Raise one side of the power shovel with the use of lifting jacks 40, placing one under each of the main cross members 13. The lifting jacks should be placed as near as possible to the inner of the timbers 9 without interfering with the movement of the crawler treads thereon. The power shovel should be raised just sufficiently to allow the crawler tread strand to pass freely under the lower idler wheels 34.

(6) Remove the four end keeper plates 19 from the ends of the truck side frame.

(7) Open roller drive chain 29 and remove the chain from the chain sprocket 30.

(8) Remove the nut 23a from the adjusting screws 20. The roller chain sprocket and spool wheel shaft assemblies can now be removed from the slotted end of the truck side members 12 by aid of slings attached to the dipper 38.

(9) Swing the shovel dipper 38 around to the opposite end of the power shovel truck and remove the non-drive spool wheel assembly in the same manner as above described, except that the end locking plate 41 is removed from the adjusting screws 20a instead of a locknut 23a.

The dismantled spool wheel assemblies are now stored out of the way on the flatcar.

(10) Attach one end of a wire rope cable or sling 36 to the tread link pin 37 of the crawler tread stand 39 nearest to the drive-end of the machine; pass it under and into the grooves of the lower idler wheels 34 and hitch the other end of the cable or sling 36 to the dipper 38, which is pointed outwards from the non-drive end as shown in Fig. 1. With the aid of the hoisting and crowding-out action of the dipper pulling on the cable 36 the crawler tread strand 39 is pulled along the timbers 9. Place half the tread strand 39 less three tread links 33 out in front of the non-drive end and leave the remaining part under the idler wheels 34 with tread links 33 left for folding up and over purposes on the tread drive sprocket 15.

(11) Sling the complete tread drive and roller chain sprocket shaft assembly including adjusting blocks 17 and screws 20 to the dipper 38. Lift and place the complete assembly on top of the tread strand 39 close to the end of the truck side frame 12. With the shaft of the assembly held horizontally, roll the assembly on the

treads and into the forked end of the side frame 12, at the same time guiding the adjusting screws 20 through the holes in the transverse webs 18.

(12) Wrap the roller drive chain 29 around the outer halves of both chain sprockets 28 and 30 and join the chain ends.

(13) Adjust the roller drive chain 29 gradually to its proper tension by turning both nuts 23, making sure that the whole tread drive sprocket and shaft assembly is kept lined up parallel with the truck side frame 12. Finally lock the whole assembly in place with the lock nuts 23a.

(14) The two end covers 19 are now replaced on the forked ends of the truck side frame and securely fastened in place.

(15) The non-driving end idler sprocket shaft assembly is slung into place on top of the tread strand 39 close up to the non-drive end of the truck side frame 12. With the shaft held horizontally the assembly is rolled on the treads and into the forked end of the side frame 12 as far as it will go. Set the adjusting screws 20a and nuts 24 in place, leaving all take-up on the adjusting screws to be made after the tread strand 39 has been completely assembled in place with ends joined.

(16) Replace the end covers 19 on the non-driving end.

(17) Lower the machine down on the crawler tread strand 39 by removing the two lifting jacks. Fold the last three tread links 33 up and over the tread drive sprocket 15 and attach a cable to the pin 37 in the last tread link. Pass the cable over the grooves of the top idler wheels 31 and hitch the free end to the tooth of the shovel clipper 38. With the machine set in travelling position and a constant tension on the cable, move the machine slowly in the direction of the dipper 38. This will draw the tread strand 39 over the tread idler sprocket 15a and top idler wheels 31. When the last two tread links 33 are in a position to fold down over the tread idler sprocket 15a, stop the machine and unhitch the cable. The two end tread links 33 remaining on the timbers 9 can now be raised and joined to the other end of the tread strand lying over the top of the side frame.

(18) The final adjustment of the tension on the crawler tread strand is made by gradually turning both nuts 24 on the adjusting screws 20a and taking up all unnecessary slack in the tread strand, making sure that the whole tread idler sprocket shaft assembly is kept parallel with the truck side frame.

The above procedure completes the conversion of one side of the power shovel from spool wheel to crawler tread assembly. The procedure is repeated for the other side of the machine by first moving the machine on the flatcar back to the starting point set out above in paragraph 1 of the conversion procedure are following the same procedure.

The power shovel when completely converted to crawler track assembly can be readily moved off the flatcar for operation on the ground by the use of a ramp set against the flatcar.

The opposite of the above procedure is followed when the power shovel is returned to the flatcar and it is desired to convert back to spool wheel drive.

At all times, the top surface of the flatcar is ready equipped to take either a spool wheeled machine or a crawler tread equipped machine and during the process of conversion one side of the machine may be equipped with spool wheels while the other side is equipped with a crawler tread, neither of which prevents the machine from being moved along the surface of the flatcar from one position to another for the purpose of facilitating the fitting or removal of the various parts of the machine moving elements. The rails 8 and the timbers 9 being flush with each other allows the crawler tread to be moved freely into position under the side frame of the machine and to straddle the rail and be aligned

with the centre line of the drive and the rail, the edges of the timbers 9 providing a ready check on the parallel alignment of the assembly. The shaft assemblies for both spool wheel and crawler tread operation are identical in their fitting into the forked end of the side frames and with the location on their shafts of the chain drive sprockets therefore the substitution of one for the other presents no problem in fitting or alignment during the conversion operation. The tensioning of the chain drive for wheel operation of the machine presents no problem except to make sure that the drive shaft assemblies hold the wheels parallel with each other. When crawler treads are to be fitted to the machine it is essential that the chain drives be tensioned before the crawler tread strands 39 are fitted and that the tread sprockets 15 are parallel with each other and aligned with the permanently fitted idler pulleys 31 and 34. The crawler tread strands 39 are tensioned at the non-driving end of the machine without affecting the setting of the drive shaft assembly and tension.

A power shovel having its main frame equipped to take alternative shaft assemblies having wheels or crawler tread sprockets and being permanently equipped with tread idler wheels, together with a railroad flatcar having rails and crawler tread timbers, offers a solution to the conversion problem, which conversion can be carried out with accuracy and a minimum of delay. Further, the conversion of the machine can be carried out in the field only with the use of equipment such as jacks and slings that can be easily handled by man power and the machine itself.

What I claim is:

1. In a power shovel or like machine which is convertible between wheel and endless track traction, in combination, a main truck frame supporting the power shovel, the said main truck frame comprising a pair of side members tied together in spaced relation, said side members being formed of two vertically disposed members assembled in spaced relation to each other to provide clearance for the traction drive elements of the machine, a drive shaft located transversely between said side members, crawler tread idler wheels journaled in said truck frame side members, a set of four wheel shaft assemblies including a traction wheel and a pair of bearing blocks, a pair of said traction wheel assemblies including a drive member, a set of four crawler tread sprocket shaft assemblies including a tread sprocket wheel and a pair of bearing blocks, a pair of said latter shaft assemblies including a drive member, said sets of shaft assemblies fitting into the ends of said truck frame as alternative wheel or crawler tread traction members, the said wheels and crawler tread sprockets being disposed between the spaced apart members of the said side frames in the same vertical plane as the said crawler tread idler wheels, drive means connecting the drive members of said shaft assemblies with the said drive shaft when the said shaft assemblies are fitted into the said truck frames, and a crawler tread strand fitted over said crawler tread sprockets and idler wheels when the crawler tread sprocket shaft assemblies are fitted to said main truck side members.

2. In a power shovel or like machine which is convertible between wheel and endless track traction, in combination, a main truck frame supporting the power shovel, the said main truck frame comprising a pair of side members being of two vertically disposed members assembled in spaced relation to each other to provide clearance for the traction drive elements of the machine, a drive shaft located transversely between the said side members, a pair of sprocket wheels on said drive shaft, the said sprocket wheels being disposed one on the inner side of each of said truck frame side members, a pair of sprocket drive chains engaging with said pair of sprocket wheels, crawler tread idler wheels journaled

in said truck frame side members and having their lower periphery projecting below the lower surface of said side members, a set of four wheel shaft assemblies including a traction wheel and a pair of bearing blocks, a pair of said wheel shaft assemblies including a drive chain sprocket wheel, a set of four crawler tread sprocket shaft assemblies including a crawler tread sprocket wheel and a pair of bearing blocks, a pair of said latter shaft assemblies including a drive chain sprocket wheel, said sets of shaft assemblies fitting into the ends of said truck frame as alternative wheel or crawler tread traction members, the said traction wheel and crawler tread sprockets being disposed between the spaced apart members of the said side frames in the same vertical plane as said crawler idler wheels, the said drive sprocket wheels of the said wheel shaft assemblies and of the said crawler tread sprocket shaft assemblies engaging with the said chain drives when the said assemblies are fitted in the said truck frames, means to tension the said chain drives through their separate shaft assemblies, means to tension the non-driving shaft assemblies independently of the driving shaft assemblies, and a crawler tread strand fitted over said crawler tread sprockets and idler wheels when the crawler tread sprocket shaft assemblies are fitted to said main truck side members.

3. In a power shovel or like machine which is convertible between wheel and endless track traction, in combination, a main truck frame supporting the power shovel, the said main truck frame comprising a pair of side members tied together in spaced relation, said side members being formed of two vertically disposed members assembled in spaced relation to each other to provide clearance for the traction drive elements of the machine, a drive shaft located transversely between said side members, a pair of sprocket wheels on said drive shaft, the said sprocket wheels being disposed one on the inner side of each of said truck frame side members, a pair of sprocket chains engaging with said pair of sprocket wheels, crawler tread idler wheels journaled on the bottom surface of said truck frame side members, the said idler wheels being disposed in the central vertical plane of the truck side frames, a set of four wheel shaft assemblies including a traction wheel and a pair of bearing blocks, a pair of said wheel shaft assemblies including a drive chain sprocket wheel, a set of four crawler tread sprocket shaft assemblies including a crawler tread sprocket wheel and a pair of bearing blocks, a pair of said latter shaft assemblies including a drive chain sprocket wheel, said sets of shaft assemblies fitting into the ends of said truck frame as alternative wheel or crawler tread traction members, the said traction wheel and crawler tread sprockets being disposed between the spaced apart members of the said side frames in the same vertical plane as said crawler tread idler wheels, the said drive sprocket wheels of the said wheel shaft assemblies and of the said crawler tread sprocket shaft assemblies engaging with the said chain drives when the said assemblies are fitted into said truck frames, means to tension the said chain drives through their separate shaft assemblies, means to tension the non-driving shaft assemblies independently of the driving shaft assemblies, and a crawler tread strand fitted over said crawler tread sprockets and idler wheels when the crawler tread sprocket shaft assemblies are fitted in said main truck side members.

4. In a power shovel or like machine which is convertible between wheel and endless track traction, in combination, a main truck frame supporting the power shovel, the said main truck frame comprising a pair of side members tied together in spaced relation, said side members being formed of two vertically disposed members assembled in spaced relation to each other to provide clearance for the traction drive elements of the machine, a drive shaft located transversely between said side members, a pair of sprocket wheels on said drive shaft, the said sprocket wheels being disposed one on the inner

side of each of said truck frame side members, a pair of sprocket drive chains engaging with said pair of sprocket wheels, crawler tread idler wheels journaled in said truck frame side members, a set of four wheel shaft assemblies including a traction wheel and a pair of bearing blocks, a pair of said traction wheel assemblies including a drive chain sprocket wheel, a set of four crawler tread sprocket shaft assemblies including a tread sprocket wheel and a pair of bearing blocks, a pair of said latter shaft assemblies including a drive chain sprocket wheel, said sets of shaft assemblies fitting into the ends of said truck frame as alternative wheel or crawler tread traction members, the said wheels and crawler tread sprockets being disposed between the spaced apart members of the said side frames in the same vertical plane as said crawler tread idler wheels, the said drive sprocket wheels of the said wheel shaft assemblies and of the said crawler tread sprocket shaft assemblies engaging with the said chain drives when the said assemblies are fitted into the said truck frames, one of the pair of said wheel shaft assemblies which include the drive chain sprocket wheel being disposed in one side frame member at one end of the truck frame and the other of said pair being disposed in the other side frame member and at the opposite end of the truck frame, a floating axle connecting the pair of wheel shaft assemblies at each end of said truck frame, means to tension the chain drives, and a crawler tread strand fitted over said crawler tread sprockets and idler wheels when the crawler tread sprocket shaft assemblies are fitted to said main truck side members.

5. In a power shovel or like machine which is convertible between wheel and endless track traction, in combination, a main truck frame supporting the power shovel, the said main truck frame comprising a pair of side members tied together in spaced relation, said side members being formed of two vertically disposed members assembled in spaced relation to each other to provide clearance for the traction drive elements of the machine, a drive shaft located transversely between said side members, a pair of sprocket wheels on said drive shaft, the said sprocket wheels being disposed one on the inner side of each of said truck frame side members, a pair of sprocket drive chains engaging with said pair of sprocket wheels, crawler tread idler wheels journaled in said truck frame side members and having their lower periphery projecting below the lower surface of the side members, a set of four wheel shaft assemblies including a traction wheel and a pair of bearing blocks, a pair of said wheel shaft assemblies including a drive chain sprocket wheel, a set of four crawler tread sprocket shaft assemblies including a crawler tread sprocket wheel and a pair of bearing blocks, a pair of said latter shaft assemblies including a drive chain sprocket wheel, said set of shaft assemblies including a drive chain sprocket wheel, said set of shaft assemblies fitting into the ends of said truck frame as alternative wheel or crawler tread traction members, the said traction wheels and crawler tread sprockets being disposed between the spaced apart members of the said side frames in the same vertical plane as said crawler tread idler wheels, the said drive sprocket wheels of the said wheel shaft assemblies and of the crawler tread sprocket shaft assemblies engaging with the said chain drives when the said assemblies are fitted into said truck frames, one of the pair of said wheel shaft assemblies which include the drive chain sprocket wheel being disposed in one side frame member at one end of the truck frame and the other of the said pair being disposed in the other side frame member and at the opposite end of the truck frame, a floating axle connecting the pair of wheel shaft assemblies at each end of said truck frame, means to tension the said chain drives through their separate shaft assemblies, means to tension the non-driving shaft assemblies of the crawler tread shaft assemblies independently of the driving shaft assemblies, and a crawler tread strand fitted over said crawler tread sprockets and

idler wheels when the crawler tread sprocket shaft assemblies are fitted to said main truck side members.

6. In a power shovel or like machine which is convertible between wheel and endless track traction, in combination, a main truck frame supporting the power shovel, said main truck frame comprising a pair of side members tied together in spaced relation, the said side members comprising vertically disposed pairs of channels spaced apart to provide clearance for the traction drive elements of the machine, a drive shaft located transversely between said side members, a pair of sprocket wheels on said drive shaft, the said sprocket wheels being disposed one on the inner side of each of said truck frame side members, a pair of sprocket drive chains engaging with said pair of sprocket wheels, crawler tread idler wheels journaled on the bottom surfaces of said truck frame side members, the said idler wheels being disposed in a vertical plane central between the pairs of channel members of the truck side frames, a set of four wheel shaft assemblies including a traction wheel and a pair of bearing blocks, a pair of said wheel shaft assemblies including a drive chain sprocket wheel, a set of four crawler tread sprocket shaft assemblies including a crawler tread sprocket wheel and a pair of bearing blocks, a pair of said latter shaft assemblies including a drive chain sprocket wheel, said sets of shaft assemblies fitting into the ends of said truck frame as alternative wheel or crawler tread traction members, the said wheels and crawler tread sprockets being disposed between the channel members of the side frames and in the same vertical plane as said crawler tread idler wheels, the said drive sprocket wheels of said wheel shaft assemblies and of the said crawler tread sprocket shaft assemblies engaging with the said chain drives when the said assemblies are fitted into said truck frames, means to tension the said chain drives through their separate shaft assemblies, means to tension the non-driving shaft assemblies independently of the driving shaft assemblies, and a crawler tread strand fitted over said crawler tread sprockets and idler wheels when the crawler tread sprocket shaft assemblies are fitted to said main truck side members.

7. In a power shovel or like machine which is convertible between wheel and endless track traction, in combination, a main truck frame supporting the power shovel,

said main truck frame comprising a pair of side members tied together in spaced relation, the said side members comprising pairs of channels spaced apart to provide clearance for the traction drive elements of the machine, 5 a drive shaft located transversely between said side members, a pair of sprocket wheels on said drive shaft, the said sprocket wheels being disposed one on the inner side of each of said truck frame side members, a pair of sprocket drive chains engaging with said pair of sprocket 10 wheels, crawler tread idler wheels journaled on the bottom surfaces of said truck frame side members, the said idler wheels being disposed in a vertical plane central between the pairs of channel members of the truck side frames and projecting below said frames, a set of four wheel shaft assemblies including a traction wheel and a 15 pair of bearing blocks, a pair of said wheel shaft assemblies including a driven chain sprocket wheel, a set of four crawler tread sprocket shaft assemblies including a crawler tread sprocket wheel and a pair of bearing blocks, a pair of said latter shaft assemblies including a 20 driven chain sprocket wheel, said set of shaft assemblies fitting into the ends of said truck frame as alternative wheel or crawler tread traction members, the said wheel and crawler tread sprockets being disposed between the 25 channel members of the side frames and in the same vertical plane as said crawler tread idler wheels and connected to said sprocket drive chains through the said driven chain sprocket wheels, means to tension the said chain drives through their separate shaft assemblies, 30 means to tension the non-driving shaft assemblies independently of the driving shaft assemblies, and a crawler tread strand fitted over said crawler tread sprockets and idler wheels when the crawler tread sprocket shaft assemblies are fitted to said main truck side members.
